UNITED STATES PATENT OFFICE

2,304,533

CIGARETTE DISPENSER

Newell N. Bright, Des Moines, Iowa

Application October 19, 1940, Serial No. 361,935

3 Claims. (Cl. 312—68)

This invention pertains more particularly to a device to be placed in stores for the purpose of containing a variety of particular kind of package article to be sold, such as packages of cigarettes, wherein the various brands of the article being sold may be prominently displayed so that the purchaser may easily and quickly select the particular brand which he wishes to purchase, and by pressing a knob provided for that purpose, which corresponds to the brand he wishes to purchase, a package of said brand will be moved into a convenient position to be grasped by the purchaser, and in connection therewith a signal device, operated by the removal of said package, to give warning to the owner of the store, or clerks employed therein, that a package is being removed from the dispenser, the purchaser at that time paying the clerk for the package.

The object of my invention is to provide a dispenser of the type above described, of simple, durable and inexpensive construction, having means whereby a comparatively large quantity of packages may be stored in a comparatively small space, and improved means for moving the packages to operative position where they may be easily removed.

A further object is to provide, in connection with the device above described, an improved signal device so constructed and arranged that a package cannot be removed from the dispenser without producing a warning signal.

A further object is to provide in a dispenser of that type employing one or more package-containing compartments adapted to receive packages arranged in vertical tiers and having means for dispensing the lower package of one of the tiers to a suitable outlet passage, improved means for advancing other tiers of packages into operative position when the first tier has been exhausted.

A further object is to provide in connection with a dispenser of the type above described, improved means for displaying the various brands of articles to be dispensed.

My invention consists in the construction, arrangement and combination of the various parts of the device, whereby the objects contemplated are attained, as hereinafter more fully set forth, pointed out in my claims, and illustrated in the accompanying drawing, in which:

Figure 1 illustrates the lower portion of the front end of my improved device, a portion of the front end being broken away to show the interior construction;

Figure 2 is a detail sectional view taken on the line 2—2 of Figure 1 showing diagrammatically the alarm system used in connection therewith;

Figure 3 is an enlarged detail sectional view taken on the line 3—3 of Figure 2.

My improved device comprises a casing having a bottom 10, a back 11, a top portion 12, and side members 13.

Supported on the back end of the bottom 10 is a bar 14, and intermediate the front and back, a second bar 15. The casing is provided with a series of partitions 16 which are spaced apart a distance slightly greater than the width of the packages 17 to be dispensed, such as packages of cigarettes, and adapted to receive between them vertical tiers of said packages. Mounted on top of the bars 14 and 15 and adjacent to each side of the corresponding partition 16 is a bar 18, in such manner that two bars 18 are provided in the chamber between two opposite partitions 16, as clearly illustrated in Figure 1 and serve to provide a floor for a number of tiers of the packages which are held in reserve. The front end of the platform 10 is provided with an upright member 19 to substantially the same height as the member 15.

Supported between the members 15 and 19 is a series of longitudinally extending blocks 20. Supported on the blocks 20 is what I shall term an ejector platform 21 which is positioned at a lower elevation than the top edges of the members 18, so that a step is provided between the upper surface of the forward ends of the members 18 and the rear end of the platform 21 from which the dispensed packages are ejected.

Hinged to the under surface of the forward end of the top member 12 is a door 22 having end members 23, a back member 24, a bottom member 25 and a front member 26 spaced from the member 24 and formed of transparent material such as glass. A space 27 is thus formed in which display packages 28 are placed. The space between the members 24 and 26 may be provided with vertical partitions 29 substantially in alignment with the partitions 16, so that the display packages in any one of the compartments formed between two of the partitions 29 may correspond to the packages formed in the chambers between the corresponding partitions 16, so that the purchaser may easily and quickly determine which of the ejector buttons 30, hereinafter to be described, to operate in order to obtain the desired brand of cigarettes.

The chambers 27 formed between the partitions 29 are open at their upper ends for receiving

the packages to be displayed, the door being elevated to its horizontal position when such packages are placed therein. The door 22 also provides a front member for the front tier of packages and has its lower edge spaced above the platform 21 a distance slightly greater than the height of one of said packages so as to provide a discharge through which the lower package of the front tier of packages may be ejected, said discharge being common to all of the spaces or chambers formed between corresponding partitions 16.

The lower edge of the member 25 is provided with a yieldable contact member 31 which extends the full width of the door 22. The front edge of the member 25 is also provided with a contact member 32 adapted to be engaged by the member 31 as it is moved upwardly to close an electric circuit 33 in which the said contacts are included, the contact 31 being positioned at a distance from the platform 21 less than the thickness or height of one of the packages to be ejected, so that the removal of one of said packages will cause the member 31 to be elevated and to make contact with the member 32, causing the circuit 31 to be closed and an alarm device 34, such as an electric bell, actuated. The circuit 33 is preferably energized by means of a step-down transformer 35 having its primary windings included in the house lighting circuit. However, a battery arrangement may be substituted for the transformer if so desired.

For ejecting the lower one of the packages from the front tier forming one of the storage compartments between the partitions 16 I have provided the following mechanism: Fixed to the left hand surface of each of the members 20, as shown in Figure 1, I have provided a pivot member or stud 36, on which is pivotally mounted a sleeve 37, the inner end of the sleeve 37 being provided with an upwardly and rearwardly inclined arm 38 terminating near the upper edge of the member 15 and adapted to operate in a slot 39 formed in the inner edge of the member 21, and of such length as to engage the inner end of a package 40 when the upper end of said member 38 is moved forwardly, and to cause said package to be moved to position beneath the member 25 where the purchaser may grasp the same between his thumb and forefinger, after which the package may be removed in the manner before described.

For actuating the sleeve 37 a downwardly extending arm 41 is provided on the inner end of the sleeve 37 to which an operating bar 42 is pivotally connected, one end of said bar extending forwardly and outwardly through an opening 43 in the member 19 and provided at its outer end with a knob 30, before referred to. A spring 44 having one end attached to the lever 41 and its other end to a pin 45 mounted in the member 20, provides means for normally moving the upper end of the lever 38 rearwardly and the knob 30 forwardly, the knobs 30 being located in such a manner as to fall in alignment with the compartments to which they are operatively connected and in alignment with the display packages corresponding with the ones to be delivered by the member 38, so that the operator may easily determine which of the knobs to actuate in order to obtain a desired brand of cigarette.

For moving another tier of packages in operative position on the platform 21 after the front tier of packages has been consumed from the 75

storage space back of said tier, I have provided an upright bar 46 between the member 11 and the rear end of the tiers of packages in storage, said member 46 being of such width as to move 5 between the members 18 and having its lower end provided with an enlarged portion 47 and its lower end slidably mounted on the bottom member 10, the head 47 serving to assist in holding the member 46 in an upright position. The front 10 face of the member 46 is provided with a pressure plate 48 which is somewhat wider than the member 46, having its lower end terminating above the members 18, the front face of the plate 48 being inclined slightly upwardly and rearwardly and having its lower end extending forwardly beyond the member 46 a distance somewhat greater than the thickness of the member 15, as illustrated by dotted lines in Figure 2, so that as the member 46 is moved forward and the last tier of packages from the storage space is moved into operative position on the platform 21, the rear edge of said tier of packages will clear the forward end of the members 15.

For operating the member 47 I have provided 25 a rod 49 slidably mounted on the members 15 and 19 and through the member 47, and provided at its rear end with a head 50 and at its front end with a knob 51, the rod being of such length that when the member 46 is at its rearward position 30 of movement, the knob 51 will be substantially near the front face of the member 19. By this arrangement it will be seen that if the knob 51 is moved forwardly, then the head 50 will engage the head 47, causing the bar 46 and the plate 35 48 to be moved forwardly, and with them all the tiers of packages supported on the bars 15, which movement will be continued until the front one 40 of said tiers is moved in position on the platform 21 with its forward edge against the inner surface of the member 24. The rod 49 may then be moved rearwardly, sliding through the members 15, 19 and 47.

When it is desired to move another tier of packages in position, the rod is again moved forwardly, causing the member 46 again to be advanced a distance equal to the length of one tier of packages.

The inclined surface of the member 48 provides means whereby the pressure will be applied to the lower one of the packages in the vertical tiers and to provide clearance between the upper packages and the front face of said member, the lower end of the member 48 projecting the member 46 so as to cause the lower package of the last tier to be moved forwardly of the ends of the member 15, as before described.

Thus, it will be seen I have provided a dispensing device of comparatively simple and cheap construction, so constructed and arranged that a different brand of packages may be carried in each of the storage compartments, and means whereby one of the packages of each of said compartments may be moved to operative position where they may be easily grasped by the purchaser, and wherein the package cannot be removed without giving a warning signal to the clerk or owner of the store who might be engaged in the sale of other goods, that the package has been removed from the dispenser, thus providing means for safeguarding the owner against the stealing of the packages, thus providing a dispensing device wherein any expensive coin-controlled devices are eliminated.

I claim as my invention:

1. In a package dispenser, a container compris-

ing a base, spaced side members, back and front members, a floor for supporting vertical tiers of packages in reserve, a delivery platform at the front end of said floor and beneath said front member to support a vertical tier of packages adjacent to said front member to be delivered from said container, the front being provided with a passage through which the bottom packages of said front tier may be ejected one at a time, means for ejecting said packages, a pressure plate for moving said reserve tiers forwardly to replace said front tier when exhausted, and means for advancing said pressure plate, the forward face of said pressure plate being inclined upwardly and rearwardly for the purpose stated.

2. A package dispenser, comprising, a base, an upright front plate fixed to the front edge of said base, a pair of transversely arranged supporting bars, one at the rear end of said base and the other intermediate the ends of said base, upright side members spaced apart and carried by the said transversely arranged bars, a floor bar adjacent to each side of the lower edge of said side members and spaced apart for supporting tiers of packages in reserve, a delivery platform supported by the intermediate transverse bar and the first said plate, said platform being lower than the upper edges of said floor bars, a front member connecting the forward ends of said side members supported above said platform and intermediate its forward and rear edges, said platform being adapted to support a tier of packages

- 5 adjacent to said front member, means for ejecting the lower one of said packages forwardly beneath said front member and on said platform, an upright pressure support behind the vertical tiers of packages in reserve and extending downwardly between said floor bars and terminating in a large portion slidably mounted beneath said bars, a rod connected to said enlarged portion slidably mounted in the intermediate transversely arranged bar and the first said upright plate, a knob mounted on the forward end of said rod, the front ends of the upper end of said pressure bar being provided with a pressure plate having its front face inclined upwardly and rearwardly.
- 10 3. In a package dispenser, a container, having a discharge opening in one side, adapted to support a series of vertical tiers of packages in reserve and a single tier of packages adjacent to said side from which packages may be ejected, means for ejecting the bottom package of said single tier from said container successively through said opening, a pressure plate slidably mounted to move toward and from said single tier and adapted to engage and move reserve tiers of packages forwardly upon forward movement of said pressure plate, with the front one of said tiers in position to replace said single tier when exhausted, the front face of said pressure plate being inclined upwardly and rearwardly, and means for actuating said pressure plate.
- 20
- 25
- 30

NEWELL N. BRIGHT.
